UNITED STATES PATENT OFFICE

ALBERT KLEIN, OF BRONX, NEW YORK

DESIGN FOR AN ASH TRAY OR THE LIKE

Application filed March 3, 1931. Serial No. 38,914. Term of patent 3½ years.

To all whom it may concern:

Be it known that I, ALBERT KLEIN, a citizen of the United States, residing in Bronx, county and State of New York, have invented a new, original, and ornamental Design for Ash Trays or the like, of which the following is a specification, reference being had to the accompanying drawings, forming part thereof.

I claim as my invention:

The ornamental design for an ash tray or the like, substantially as shown.

ALBERT KLEIN.
